ELECTRIC CIRCUIT CONTROLLING
APPLIANCE

Joseph Sachs, West Hartford, Conn.

Application April 13, 1935, Serial No. 16,133

16 Claims. (Cl. 200—50)

The invention relates particularly to an electric circuit controlling appliance which includes fuse contacts and fuses in at least two legs or sides of the circuit, and which is primarily adapted and intended to be used in an electric circuit ahead of the meter therein.

In order to obtain current in a three wire system without the current being measured by the meter, it has been a prevalent practice to remove one of the fuses ahead of the meter, or to intentionally blow one of the fuses, and to then place a jumper or by-pass in engagement with the fuse contacts so as to make a transverse electrical connection from one side of the circuit to the other side. In this way both sides of the load circuit are connected with one side of the supply circuit and the user obtains current for this entire load; but inasmuch as the connection from the other side of the supply circuit to the meter is broken, the meter does not operate.

One of the principal objects of the present invention is to provide an electric circuit controlling appliance which includes two fuses in two legs of the circuit, and which has, in conjunction with the fuses, a sliding cover and associated parts which serve when the cover is closed to prevent the maintenance of any transverse electrical connections, this being accomplished by providing an element on the cover which directly interferes with any such transverse electrical connection during closing or attempted closing of the cover. Preferably the said element on the cover is a longitudinal shield which cooperates with the base when the cover is fully closed so as to eliminate any transverse opening or passage between one pair of fuse contacts or the fuse therein and the other pair of fuse contacts or the fuse therein.

Preferably, a circuit controlling appliance embodying the invention includes switching means in series with the fuses; and when switching means are provided I prefer to provide an interlocking mechanism which prevents the sliding cover from being opened when the switch is closed and which prevents the switch from being closed when the sliding cover is open.

A further object of the invention is to provide an improved interlocking means between a sliding fuse cover and a switch operating handle.

Other objects of the invention will be apparent from the following specification and claims.

In the accompanying drawings I have shown the embodiment of the invention which I now deem preferable, but it will be understood that the drawings are intended for illustrative purposes only and are not to be construed as defining or

limiting the scope of the invention, the claims forming a part of this specification being relied upon for that purpose.

Of the drawings:

Fig. 1 is a front view of an electric circuit controlling appliance embodying the invention. 5

Fig. 2 is a view similar to Fig. 1 but showing the switch handle in its open-circuit position and showing the sliding fuse cover in its open position. In this view certain parts are broken away 10 to show other parts more clearly.

Fig. 3 is a vertical sectional view taken along the line 3—3 of Fig. 1.

Fig. 4 is a horizontal sectional view taken along the lines 4—4 of Figs. 1 and 3. 15

Referring to the drawings, 1 represents a stationary insulating base, on the front of which are two pairs of fuse receiving contacts 2, 2 and 3, 3, the contacts of the two pairs being spaced apart transversely. The fuse contacts 2, 2 and 3, 3 are shown as being adapted for receiving a fuse of the knife blade type, but it will be understood that the invention is not necessarily so limited. 20

Associated with the base 1 and the fuse contacts 2, 2 and 3, 3 is a cover 4 which is mounted to slide longitudinally in a plane parallel with the front of the base. When the cover is in its closed position, as shown in Fig. 1, the fuse contacts and the fuses therein are entirely enclosed and protected, and when the cover is in its open position, as shown in Fig. 2, the fuse contacts and the fuses therein are readily accessible. 25

In order to prevent the maintenance of any transverse electrical connection between the fuse contacts of one pair and the fuse contacts of the other pair, I provide an element such as 5 projecting rearward from the cover and movable longitudinally between the two pairs of fuse contacts and the fuses therein, while the cover is being moved in the closing direction. When the sliding cover 4 is moved from its open position toward its closed position the element 5 moves longitudinally, and if any wire or other transverse electrical connection has been put in place from a fuse 40 contact of one pair to a fuse contact of the other pair this wire is either detached or broken by the moving element 5 or the wire serves to prevent movement of the element and thus prevent closing of the cover. 45

The details of the rearward projecting element 5 may be widely varied, but preferably and as shown it is in the form of a longitudinal shield which is movable between the two pairs of fuse contacts. This shield overlaps a portion of the 55

base and preferably enters a groove 6 formed in the base, as shown in Figs. 2 and 4. Preferably and as shown, the base is provided with an integral barrier 7 which projects forward from the main body of the base and is positioned between the fuse contacts of the two pairs; and the before-mentioned groove 6 is formed in the barrier 7.

The sliding element 5 for interfering with the transverse wire or connection is distinctly different in its action from pivoted shields which have heretofore been proposed to be used. A pivoted shield merely serves to press a transverse conductor or connection firmly against the base but it has no tendency whatever to break or detach the said connection or conductor. Furthermore, with a pivoted shield carried by a pivoted cover there is nothing to prevent the substantial closing of the cover notwithstanding the presence of an unbroken or undetached transverse connection between the fuses or their contacts. Unless the parts are constructed and fitted much more accurately than is customary or practicable in the manufacture of switches, the presence of a thin transverse conductor will not interfere with the closing of a pivoted cover. However, with the sliding cover and the sliding projecting element there is an actual interference between the element and the transverse connection which definitely and unavoidably results either in the detachment or breaking of the connection or in the blocking of the projecting element so that the cover cannot be closed.

When the cover is entirely closed the overlapping means, consisting of the shield 5 and the barrier 7 with its groove 6, completely eliminate any transverse opening or passage between the one pair of fuse contacts or the fuse therein and the other pair of fuse contacts or the fuse therein. It will be apparent from the drawings that the shield approximately fits the groove, thus making it impossible for even a very small wire to lie between the overlapping surfaces.

Preferably, the base 1 is at least partly enclosed in a suitable casing or box such as 8. The box 8 has a front wall or cover 9 having an opening therein, and the fuse contacts and fuses are accessible at the said opening. Preferably and as shown, the base 1 has a front portion 10 which projects through and substantially closes the opening in the front wall 9. This front portion 10 may have peripheral walls which, together with the barrier 7, entirely surround the fuse contacts and the fuses at the sides and ends thereof.

The slideable cover 4 is carried by the front wall 9 of the box and is offset toward the front and is shaped to pass in front of the fuse contacts and the fuses and in front of the forward projecting portion of the base, as clearly indicated in Fig. 4. As shown, the cover 4 has laterally projecting flanges 11 and 12 at its edges which are engaged and guided by suitable guiding means secured to the said front wall 9. It will be observed that the shield 5 carried by the cover 4 is in front of the plane of the front wall or cover 9 of the box, and that the said shield is movable in front of the said front wall or cover.

When the cover 4 is offset toward the front, as shown, the forward projecting portion is closed at the bottom by a transverse wall 13, and the lower end of the shield 5 engages the said wall. The upper end of the shield preferably projects beyond the upper end of the cover. Preferably, forward projecting transverse partitions are provided on the front wall of the box adjacent the

opposite top and bottom edges of the opening therein. The upper partition is shown at 14 and is provided with a downward extending flange 14a which surrounds and encloses the upper end of the cover 4 when the cover is in closed position, as shown in Fig. 1. The partition 14 is provided with a slot through which the upper end of the shield 5 projects. The lower partition is shown at 15, this being immediately adjacent the cover wall 13 when the cover is in closed position. The partition 15 has a slot therein through which the shield 5 extends.

Preferably, a switching means is associated with the fuse contacts and the fuses, and one suitable form of switching means is shown in the drawings, although the invention is not limited to the particular switching means disclosed.

As shown, two transversely extending insulating blocks 16 and 17 are secured to the rear wall of the box 1. Mounted on the block 16 are two forward projecting transversely spaced conducting brackets 18 and 19 which partly support the fuse base 1 and which are electrically connected with the lower fuse contacts 2 and 3. Electrical connections between the fuse contacts and the respective brackets 18 and 19 are established by means of conducting straps 20, 20 and screws 21, 21. The screws 21, 21 not only insure the electrical connections but they also serve to mechanically connect the base 1 with the brackets. 30

Also secured to the insulating block 16 and spaced transversely from the brackets 18 and 19 are forward projecting conducting straps 22 and 23. Wire terminals 24 and 25 are connected respectively to the straps 22 and 23. Mounted upon and electrically connected with the several straps and brackets are pairs of stationary switch contacts 26, 27 and 28, 29. For making and breaking electrical connection between the switch contacts of the respective pairs there are provided movable switching members each consisting of a flat insulating plate 30 and a conducting element 31 carried thereby and having contact surfaces at opposite sides of the plate, these opposite contact surfaces being adapted to engage the corresponding stationary contacts. Each plate 30 is perpendicular to the front surface of the block 16 and to the rear surface of the fuse base 1, and it is guided by the said surfaces for rectilinear movement upward or downward parallel with the rear wall of the enclosing box. In order that the plate may be additionally guided, it is preferably provided with a rearward projection 30a which directly engages with the rear wall of the box. For operating the switching members there is provided a pivoted crank or bail 32 which is mounted in the side walls of the box and which is provided with an operating handle 33 on the exterior of the box at one side thereof, preferably the right side. The crank 32 extends through slots 30b in the insulating plates 30.

Mounted on the upper insulating block 17 are two forward projecting transversely spaced conducting brackets 34 which also partly support the fuse base 1 and which are electrically connected with the upper fuse contacts 2 and 3. Electrical connections between the fuse contacts and the respective brackets 34 are established by means of conducting straps 35, 35 and screws 36, 36. The screws 36, 36 not only insure the electrical connections but they also serve to mechanically connect the base 1 with the brackets 34. Electrically connected with the brackets 34 are wire terminals 37.

When the handle 33 is in the upper position shown in Fig. 3, the switching members are held in the position shown by full lines in the same figure, and electrical connection is established between the stationary switch contacts of each pair, thus electrically connecting the wire terminals 24 and 25 with the lower fuse contacts 2 and 3. When the handle is moved downward to the lower position shown in Fig. 3, the switching members are moved upward to the position shown by dotted lines in the same figure, thus breaking the electrical connection between the stationary switch contacts of each pair. Thus by operating the handle 33 and closing and opening the switch, electrical connection can be established or broken between the wire terminals 24 and 25 at the bottom and the wire terminals 31 at the top.

Preferably, wire terminals 38, 38 are provided for the connection of neutral wires. These terminals may be mounted on a projection 39 on the lower insulating block 16.

Preferably, an interlocking mechanism is provided which positively prevents the cover 4 from being moved to open position when the switch handle is in closed-circuit position and which positively prevents the switch handle from being moved to closed-circuit position when the cover is in open position. So far as the broader aspects of the invention are concerned, I do not limit myself to any particular form of interlocking mechanism; but preferably and in accordance with a more specific phase of the invention the interlocking mechanism is constructed as shown and in accordance with the following description.

Supported on the front wall of the box is an interlock plate 40 which is movable laterally into a projecting position, as shown in Fig. 2, wherein it holds the handle 33 in open-circuit position, or into a non-projecting position, as shown in Fig. 1, in which position it is positively held by the handle 33 when the latter is in closed-circuit position. Preferably, the plate 40 is mounted for pivotal movement about a pivot stud at 41.

Co-acting means are provided on the interlock plate 40 and on the slidable cover 4 whereby the plate is automatically moved to its projecting position when the cover is moved to open position and whereby the plate is automatically moved to its non-projecting position when the cover is moved to its closed position. Preferably, this co-acting means is of the cam-and-follower type, as shown. The flange 12 of the cover 4 is provided with a laterally projecting wing 12a which is behind the interlock plate 40 and which carries a forward projecting stud 42. The plate 40 is provided with a cam slot 43 through which the stud 42 extends. The main portion of the slot 43 is so located as to be parallel with the direction of movement of the slide 4 and of the stud 42 when the said plate 40 is in its projecting position. The cam slot 43 has another portion 43a which is at an angle to the said first portion, as clearly shown in Figs. 1 and 2. Preferably, a plate 44 is provided which is secured to the front wall 9 of the box and which is positioned in front of the interlock plate 40. As shown, this front plate 44 has a slot 45 therein through which the stud 42 projects.

With the cover 4 in its lower or open position, as shown in Fig. 2, the interlock plate 40 is in its projecting position and the stud 42 is at the lower end of the cam slot 43. As the cover is moved upward toward its closed position the stud 42 travels along the main parallel portion of the slot 43, the plate 40 remaining in its projecting position. When the cover has nearly reached its fully

closed position, preferably having entered the flange 14a, the stud 42 enters the short angular portion 43a of the cam slot, thus moving the plate 40 laterally from its projecting position, as shown in Fig. 2, to its non-projecting position, as shown in Fig. 1. When the cover is moved in the opposite direction from its closed position to its open position the movement of the plate 40 is opposite to that described.

It will be apparent that, with the cover in its lower position, as shown in Fig. 2, and with the interlock plate in its projecting position, the handle 33 cannot be moved upward to close the circuit. With the cover in its closed position, as shown in Fig. 1, and with the interlock plate in its non-projecting position, the handle 33 can be moved upward to close the circuit; but when it is in its upper circuit-closing position the interlock plate 40 cannot be moved laterally to its projecting position and hence the cover cannot be moved downward to expose the fuses or the fuse contacts.

I have already described in detail the action of the overlapping parts on the cover 4 and on the base 1 in preventing the maintenance of any transverse electrical connection from one side of the circuit to the other when the cover is closed. It will be obvious that these parts co-operate directly with the switch and the interlocking mechanism which have now been fully described. With the switch open and with the cover open, a transverse electrical connection can easily be put in place from the fuse or fuse contacts at one side to the fuse or fuse contacts at the other side; but inasmuch as the switch is open such transverse electrical connection would be entirely without function. It is impossible to close the switch unless the cover has first been closed, but as already explained, the cover cannot be closed with a transverse electrical connection in place. Either the transverse electrical connection is broken by the closing of the cover or the said transverse connection entirely prevents the cover from being closed. If the transverse connection is broken by the closing of the cover, the intended theft of current is defeated; or if the transverse connection prevents the cover from being closed, the switch necessarily remains open and the customer can obtain no current at all.

What I claim is:

1. In a device of the class described, the combination of an insulating base, two pairs of fuse receiving contacts on the front of the base and spaced apart transversely, a cover for the fuse contacts and for fuses therein which cover is mounted to slide independently of the fuse contacts and the fuses longitudinally in a plane parallel with the front of the base, and an element projecting rearward from the cover and movable between the two pairs of fuse contacts and the fuses therein while the cover is being moved in the closing direction, the said rearward projecting element during the said movement cooperating with the base so as to directly interfere with any transverse electrical connection between one pair of fuse contacts or the fuse therein and the other pair of fuse contacts or the fuse therein with the result that the said connection is broken or detached or that the cover is prevented from closing.

2. In a device of the class described, the combination of an insulating base, two pairs of fuse receiving contacts on the front of the base and spaced apart transversely, a cover for the fuse

contacts and for fuses therein which cover is mounted to slide independently of the fuse contacts and the fuses longitudinally in a plane parallel with the front of the base, and a rearward projecting longitudinal shield carried by the cover at the rear thereof and movable between the two pairs of fuse contacts and the fuses therein while the cover is being moved in the closing direction, the said shield during the said movement cooperating with the base so as to directly interfere with any transverse electrical connection between one pair of fuse contacts or the fuse therein and the other pair of contacts or the fuse therein with the result that the said connection is broken or detached or that the cover is prevented from closing and the said shield when the cover is fully closed transversely overlapping the base so as to eliminate any transverse opening or passage between one pair of fuse contacts or the fuse therein and the other pair of fuse contacts or the fuse therein.

3. In a device of the class described, the combination of an insulating base having a longitudinal slot in the front thereof, two pairs of fuse receiving contacts on the front of the base and spaced apart transversely at opposite sides of the slot, a cover for the fuse contacts and for fuses therein which cover is mounted to slide independently of the fuse contacts and the fuses longitudinally in a plane parallel with the front of the base, and an element projecting rearward from the cover and movable in the said slot between the two pairs of fuse contacts and the fuses therein, the said rearward projecting element cooperating with the base at the slot therein so as to directly interfere during the movement of the cover in the closing direction with any transverse electrical connection between one pair of fuse contacts or the fuse therein and the other pair of contacts or the fuse therein with the result that the said connection is broken or detached or that the cover is prevented from closing.

4. In a device of the class described, the combination of an insulating base having a forward projecting stationary longitudinal barrier thereon, two pairs of fuse receiving contacts positioned respectively at opposite sides of the barrier, a cover for the fuse contacts and for fuses therein which cover is mounted to slide independently of the fuse contacts and the fuses longitudinally in a plane parallel with the front of the base, and an element projecting rearward from the cover immediately adjacent the barrier, the said element cooperating with the barrier while the cover is being moved in the closing direction so as to directly interfere with any transverse electrical connection between the fuse contacts and fuses at opposite sides of the barrier with the result that the said connection is broken or detached or that the cover is prevented from closing.

5. In a device of the class described, the combination of an insulating base having a forward projecting stationary longitudinal barrier thereon, two pairs of fuse receiving contacts positioned respectively at opposite sides of the barrier, a cover for the fuse contacts and for fuses therein which cover is mounted to slide independently of the fuse contacts and the fuses longitudinally in a plane parallel with the front of the base, and a rearward projecting longitudinal shield on the cover immediately adjacent the barrier, the said shield cooperating with the barrier while the cover is being moved in the closing

direction so as to directly interfere with any transverse electrical connection between the fuse contacts and fuses at opposite sides of the barrier with the result that the said connection is broken or detached or that the cover is prevented from closing and the said shield when the cover is fully closed transversely overlapping the barrier so as to eliminate any transverse opening or passage between one pair of fuse contacts or the fuse therein and the other pair of fuse contacts or the fuse therein. 10

6. In a device of the class described, the combination of an insulating base having a forward projecting stationary longitudinal barrier thereon which barrier has a longitudinal slot therein, two pairs of fuse receiving contacts positioned respectively at opposite sides of the barrier, a cover for the fuse contacts and for fuses therein which cover is mounted to slide independently of the fuse contacts and the fuses longitudinally in a plane parallel with the front of the base, and a longitudinal shield on the cover projecting rearward into the slot in the barrier, the said shield cooperating with the barrier while the cover is being moved in the closing direction so as to directly interfere with any transverse electrical connection between the fuse contacts and fuses at opposite sides of the barrier with the result that the said connection is broken or detached or that the cover is prevented from closing and the said shield when the cover is fully closed cooperating with the barrier to eliminate any transverse opening or passage between one pair of fuse contacts or the fuse therein and the other pair of fuse contacts or the fuse therein. 15 20 25 30 35

7. The combination of an enclosing box having an opening in the front wall thereof, an insulating base having a front portion projecting through and substantially closing the front opening in the box, two pairs of fuse receiving contacts positioned on the projecting portion of the base and spaced apart transversely, a longitudinally slideable cover mounted on the front of the box and shaped to pass in front of the fuse contacts and in front of fuses therein, and an element projecting rearward from the cover and movable in front of the front wall of the box and between the two pairs of fuse contacts and the fuses therein while the cover is being moved in the closing direction, the said rearward projecting element during the said movement cooperating with the base so as to directly interfere with any transverse electrical connection between one pair of fuse contacts or the fuse therein and the other pair of contacts or the fuse therein with the result that the said connection is broken or detached or that the cover is prevented from closing. 40 45 50 55

8. The combination of an enclosing box having an opening in the front wall thereof, an insulating base having a front portion projecting through and substantially closing the front opening in the box, two pairs of fuse receiving contacts positioned on the projecting portion of the base and spaced apart transversely, a longitudinally slideable cover mounted on the front of the box and shaped to pass in front of the fuse contacts and in front of fuses in said contacts, and a shield carried by the cover at the rear thereof and movable in front of the front wall of the box, the said shield being between the two pairs of fuse contacts and the fuses therein when the cover is in closed position and the said shield directly cooperating with the base to prevent the maintenance of any electrical connection 75 60 65 70 75

between one pair of fuse contacts or the fuse therein and the other pair of fuse contacts or the fuse therein.

9. The combination of an enclosing box having an opening in the front wall thereof, an insulating base having a front portion projecting through and substantially closing the front opening in the box, the said projecting portion of the base including a longitudinal barrier, two pairs of fuse receiving contacts positioned on the projecting portion of the base at opposite sides of the said barrier, a longitudinally slideable cover mounted on the front of the box and shaped to pass in front of the barrier and the fuse contacts and in front of fuses in said contacts, and a shield carried by the cover at the rear thereof and movable in front of the front wall of the box, the said shield overlapping the barrier and serving when the cover is closed to prevent the maintenance of any electrical connection between the fuse contacts and fuses at opposite sides of the barrier.

10. The combination of an enclosing box having an opening in the front wall thereof, an insulating base having a front portion projecting through and substantially closing the front opening in the box, the said projecting portion of the base including a longitudinal barrier having a longitudinal slot therein, two pairs of fuse receiving contacts positioned on the projecting portion of the base at opposite sides of the said barrier, a longitudinally slideable cover mounted on the front of the box and shaped to pass in front of the barrier and the fuse contacts and in front of fuses in said contacts, and a shield carried by the cover at the rear thereof and movable in front of the front wall of the box, the said shield entering the slot in the barrier and serving when the cover is closed to prevent the maintenance of any electrical connection between the fuse contacts and fuses at opposite sides of the barrier.

11. The combination of an enclosing box having an opening in the front wall thereof, forward projecting transverse partitions on the front wall adjacent opposite edges of the opening therein which partitions have slots therein, an insulating base having a front portion projecting through and substantially closing the front opening in the box, two pairs of fuse receiving contacts positioned on the projecting portion of the base and spaced apart transversely, a longitudinally slideable cover mounted on the front of the box and shaped to pass in front of the fuse contacts and in front of fuses in said contacts, and a shield carried by the cover at the rear thereof and movable in front of the front wall of the box and through the slots in the partitions, the said shield being between the two pairs of fuse contacts and the fuses therein when the cover is in closed position and the said shield directly cooperating with the base to prevent the maintenance of any electrical connection between one pair of fuse contacts or the fuse therein and the other pair of fuse contacts or the fuse therein.

12. In a fused electric switch, the combination of an insulating base, two pairs of fuse receiving contacts on the front of the base and spaced apart transversely, two stationary switch contacts electrically connected respectively with one fuse contact of each pair, movable switching means associated with the stationary contacts to open and close the circuit, a cover for the fuse contacts and for fuses therein which cover is mounted to slide longitudinally in a plane parallel with the front of the base, interlocking

means preventing movement of the switching means to closed circuit position when the cover is in open position and preventing movement of the cover to open position when the switching means is in closed circuit position, and an element projecting rearward from the cover and movable between the two pairs of fuse contacts and the fuses therein while the cover is being moved in the closing direction, the said rearward projecting element during the said movement 10 cooperating with the base so as to directly interfere with any transverse electrical connection between one pair of fuse contacts or the fuse therein and the other pair of contacts or the fuse therein with the result that the said connection 15 is broken or detached or that the cover is prevented from closing.

13. In a fused electric switch, the combination of an insulating base, two pairs of fuse receiving contacts on the front of the base and spaced apart 20 transversely, two stationary switch contacts electrically connected respectively with one fuse contact of each pair, movable switching means associated with the stationary contacts to open and close the circuit, a cover for the fuse contacts 25 and for fuses therein which cover is mounted to slide longitudinally in a plane parallel with the front of the base, interlocking means preventing movement of the switching means to closed circuit position when the cover is in open position 30 and preventing movement of the cover to open position when the switching means is in closed circuit position, and cooperating means on the slideable cover and on the stationary base which overlap each other when the cover is in closed 35 position so as to eliminate any transverse opening or passage between one pair of fuse contacts or the fuse therein and the other pair of fuse contacts or the fuse therein.

14. The combination of an enclosing box having an opening in the front wall thereof, an insulating base having a front portion projecting through and substantially closing the front opening in the box, two pairs of fuse receiving contacts positioned on the projecting portion of the 45 base and spaced apart transversely, stationary switch contacts electrically connected respectively with one fuse contact of each pair, movable switching means associated with the stationary contacts to open and close the circuit, a longitudinally slideable cover mounted on the front of the box and shaped to pass in front of the fuse contacts and in front of fuses in said contacts, interlocking means preventing movement of the switching means to closed circuit position when 50 the cover is in open position and preventing movement of the cover to open position when the switching means is in closed circuit position, and a shield carried by the cover at the rear thereof and movable in front of the front wall 55 of the box, the said shield being between the two pairs of fuse contacts and the fuses therein when the cover is in closed position and directly cooperating with the base to prevent the maintenance of any electrical connection between one pair of 60 fuse contacts or the fuse therein and the other pair of fuse contacts or the fuse therein.

15. In a fused electric switch, the combination of an enclosing box having an opening in the front wall thereof, fuse receiving contacts positioned to be accessible at the said opening, switching means in the box electrically connected with the fuse contacts and adapted to open and close the circuit, a handle at one side of the box for operating the said switching means, a slideable 70 75

- cover for the fuse contacts and for fuses therein, means for guiding the cover for longitudinal movement and for preventing lateral movement thereof, a plate pivotally supported on the front wall of the box at the front of the said wall and movable laterally into a projecting position wherein it holds the handle in open-circuit position or into a non-projecting position in which it is positively held by the handle when the latter is in closed-circuit position, and coacting cam-and-follower means on the plate and on the 5
10
15
16. In a fused electric switch, the combination of an enclosing box having an opening in the front wall thereof, fuse receiving contacts positioned to be accessible at the said opening, switching means in the box electrically connected with the fuse contacts and adapted to open and close
20

the circuit, a handle at one side of the box for operating the said switching means, a slidable cover for the fuse contacts and for fuses therein, means for guiding the cover for longitudinal movement and for preventing lateral movement thereof, a plate pivoted to the front wall of the box and movable laterally into a projecting position wherein it holds the handle in open-circuit position or into a non-projecting position in which it is positively held by the handle when the latter is in closed-circuit position, the said plate having a cam slot therein one portion of which is parallel with direction of cover movement when the plate is in projecting position and another portion of which is at an angle to the first said portion, and a follower stud on the slidable cover entering the cam slot and serving to automatically move the plate to its projecting position when the cover is moved to open position and serving to automatically move the plate to its non-projecting position when the cover is moved to closed position. 10
